UNITED STATES PATENT OFFICE

2,092,554

MATRIX CASE

Philip P. Merrill, Evanston, Ill., assignor to Ludlow Typograph Company, Chicago, Ill., a corporation of Illinois

Application August 24, 1936, Serial No. 97,691

16 Claims. (Cl. 276—44)

My invention relates to cases provided, by way of example, as trays or drawers, for holding matrices from which printing line slugs are cast, the cases being formed with compartments for receiving the different matrices comprising the font and which are commonly provided with ears at the upper portions of their ends extending in opposite directions from the bodies of the matrices.

16 One of my objects is to provide a case of such construction as will permit of the receiving into its several compartments, as desired, matrices of the kind referred to, of either of two overall lengths, as produced in practice, while avoiding obstruction between the ears of matrices of the larger size disposed in parallel compartments, in the relative sliding of these matrices in the compartments.

Another object is to provide a construction whereby the compartments of the case may be quickly and easily conditioned for matrices for the forming of roman type characters, and of rectangular shape in plan, or the forming of characters of italic type, of non-rectangular parallelogram shape in plan, as desired, where the case when supported for the selecting therefrom of the matrices to be used extends in rearwardly and upwardly inclined position as in common practice and the columns of matrices rest at their lower ends against abutment surfaces.

30 Heretofore in practice it has been necessary to provide separate cases for the matrices of different overall lengths, thus requiring an unduly large number of cases involving relatively large expense of equipment and requiring considerable space for the latter. My present invention, by reason of the adaptability of the case for the storing of matrices of different overall lengths and of different shapes, greatly reduces the amount of equipment required for storing the matrices.

Another object is to provide as a part of the case means whereby the operator may conveniently and quickly determine, before inserting into the holders commonly provided to receive the composed matrices, the length, as for example in picas, of the line composed by the selected matrices; and other objects as will be manifest from the following description.

Referring to the accompanying drawings, 50 Figure 1 is a perspective view of a matrix cabinet of a common form and provided with matrix drawers embodying my invention and supported therein in upwardly and rearwardly inclined position and slidable therefrom through a side of the cabinet to a position rendering the

matrices therein accessible for withdrawal, one of the drawers being shown as partially withdrawn from the cabinet;

Figure 2 is a fragmentary sectional view taken at the line 2 on Fig. 1 and viewed in the direction of the arrow;

Figure 3 is a fragmentary perspective view of a portion of one of the rails which form the matrix compartments;

Figure 4 is a similar view of one of the cross rails adjacent the rail shown in Fig. 3;

Figure 5 is a section taken at the line 5 on Fig. 9 and viewed in the direction of the arrow;

Figure 6 is a perspective view of a construction of pillow block embodying my invention and which may be used in the case referred to as an abutment for a column of matrices of non-rectangular parallelogram shape in plan;

Figure 7 is a similar view of another form in which the pillow block may be provided;

Figure 8 is a similar view of still another form in which the pillow block may be provided;

Figure 9 is an enlarged plan view of the inner end portion of the matrix case shown in Fig. 1;

Figure 10 is a fragmentary perspective view of adjacent end portions of compartment-forming rails illustrating the corner construction, these parts being shown separated but in related position;

Figure 11 is an enlarged fragmentary sectional view, taken at the line 11—11 on Fig. 9 and viewed in the direction of the arrows;

Figure 12 is a fragmentary sectional view taken at the line 12—12 on Fig. 11 and viewed in the direction of the arrows;

Figure 13 is a perspective view of one of the similar ends of certain of the compartment-forming cross rails;

Figure 14 is a fragmentary perspective view of one of the similar compartment-forming side rails;

Figure 15 is a sectional view, taken at the line 15—15 on Fig. 11 and viewed in the direction of the arrows;

Figure 16 is an enlarged sectional view taken at the line 16—16 on Fig. 9 and viewed in the direction of the arrows;

Figure 17 is an enlarged sectional view taken at the line 17—17 on Fig. 9 and viewed in the direction of the arrows;

Figure 18 is a face view of one of the similar adjustable cross members forming walls of certain of the compartments;

Figure 19 is a similar view of a modification of the cross member shown in Fig. 18; and

Figure 20, a fragmentary plan view of a modification of the drawer.

Referring to the matrix-case-holding cabinet shown in Fig. 1 and which is of common form, it comprises a housing structure, or casing, 20, provided with guides (not shown) on which matrix drawers, represented at 21 and embodying my invention, are supported in upwardly and rearwardly inclined position and adapted to be drawn through a side of the housing 20 to a position in which the several compartments of the drawers, hereinafter described, are accessible, one of the drawers being shown as partially withdrawn to the position referred to.

15 The drawers 21 are each of the same construction, each comprising a rectangular frame 22 formed of a top member 23, a bottom member 24, side members 25 and 26, and a plate-like member 27 forming a bottom for the case.

20 Extending parallel with the frame member 25 and spaced therefrom as shown, is a bar 28 connected with the top and bottom members 23 and 24 and forming therewith and with the frame member 25 a compartment 29 extending substantially the full height of the drawer, a block 30 having a recess 31 in its upper face, being secured in the lower end of this compartment. A scale represented at 32 and graduated in picas is provided on the frame member 25 and serves as a means for readily determining the length, in picas, of a line of matrices selected by the operator in the forming of the desired line composition and assembled by him in the compartment 29.

35 The opposing faces of the frame member 25 and the bar 28 are provided with rails 33 and 34 notched, as represented at 35, to receive depending legs 36 provided on the ends of cross plates 37, which form adjustable compartment end 40 walls for dividing the compartment 29 into a number of matrix storing compartments of the desired sizes, as for example to store extra matrices, it being understood that by rendering these cross wall forming members removable the compartment 29 may be freed of obstruction for the gauging of a line of composed matrices as above pointed out.

The remainder of the case is divided into a relatively large number of compartments 38 for receiving the matrices comprising the font. The compartments 38 are formed in the particular construction shown by providing a series of parallel spaced apart terminal side rails 39, intermediate parallel spaced apart side rails 43, the latter being shown as of inverted U-shape in cross section, and horizontal spaced apart parallel cross rails 41 intersecting the rails 39 and 40, all disposed within the space bounded by the members 23, 24, 25 and 28.

60 The rails referred to may be secured together and held in place within the frame, in any suitable way, as for example as shown and as will now be described.

The terminal side rails 39 and the lowermost cross rail 41, the terminal side rails being shown as of less thickness than the rails 40, are secured to the members 28, 26 and 24 respectively, as for example by screws as represented at 39a of the rail 39 shown in Fig. 2, and the ends of the lower cross rail 41 are interlocked with the lower ends of the side rails 39 as shown in Fig. 10, namely by providing a lug 42 on the lower end of the rail 39 and providing in the adjacent end of the lowermost rail 41, between its upper and 75 lower surface, a notch 43 to receive the lug 42.

The ends of the others of these cross rails 41 are provided between their upper and lower surfaces with recesses 44 affording upper and lower lugs 45 and 46, respectively, the lower lugs 46 entering downwardly opening notches 47 in the undersides of the rails 39 and the upper lugs 45 laps the rails 39 as shown in Figs. 2-4. The intermediate rails 40 are provided at their lower ends with lugs 48 which extend into downwardly opening recesses 49 in the lower one of the cross rails 41 (Fig. 5). The others of the cross rails 41 are provided at their ends with lugs 50 (Figs. 9 and 13) which lap the upper surfaces of the side rails 39 and at their points of intersection with the rails 40 are provided with downwardly opening recessed portions 51 which interfit with upwardly recessed portions 52 of the rails 40 (Figs. 11-14).

In accordance with one phase of my invention, the side rails of the compartments 38 are of such width and are so spaced apart as to cause these compartments to be of a width adapting them to receive the bodies 53 of one size of matrix, as for example having an overall length of 1½ inches and represented at 54, with the ears 55 of the matrices resting on these rails with sufficient clearance between the ears of the matrices in adjacent parallel compartments as not to cause these ears to offer any obstruction to free sliding of the matrices in the compartments, as shown of the matrices in Figs. 9 and 16, and to adapt these compartments to receive, in their entirety, between these side rails, matrices of another size, as for example having an overall length of 1½ inches and represented at 56, as shown of the matrix in Fig. 17 and of some of the matrices of Fig. 9, thus adapting the case for the storing in the compartments 38 of matrices of different overall lengths, as desired.

According to that phase of my invention 40 whereby matrices, either of the large or small size and of either rectangular shape in plan as in the case of matrices of the roman character type, or of non-rectangular parallelogram shape in plan as in the case of matrices of the italic 45 type, may be stored in any of the compartments 38, I provide pillow blocks adapted to be inserted into the lower ends of the compartments 38 at will to adapt these compartments for matrices of non-rectangular parallelogram shape in plan, 50 such, for example, as those shown at 57 (Fig. 9), and readily removed therefrom when the compartments are to be used for the roman type of matrix.

A number of the many forms in which such 55 pillow blocks may be provided are illustrated. Thus in Figs. 6-9 I have shown a construction of such block which may be made of sheet metal, as for example steel, and comprising a web portion 58 having upper and lower flanges 59 and 60, 60 respectively, thereon, the lower flange 60 being notched along its outer edge, intermediate its ends, as represented at 61 to provide spaced apart tongues 62, and the upper flange 59 provided at its outer edge with a portion 63 of concavo-convex shape in cross section, presenting a downwardly turned edge portion 64. The web portion 58 of the block is inclined to the plane of the lugs 62 and the edge 64 at an angle corresponding to the angle at which the longer edges 65 70 of the matrices 57 extend relative to the shorter edges 66 thereof as shown, whereby the pillow blocks when inserted into the compartments are conformingly contacted at their web portions 58 by the inclined portions of the lower ones of the 75

columns of italic matrices charged into these compartments and form abutments therefor.

The cross rails 41 are notched along their under surfaces as represented at 67 to receive the tongues 62 of the pillow blocks when applied to the operative position shown in Fig. 9, the upper edges of the cross rails 41 being received within the concave portions 63 of the pillow blocks.

10 The form of pillow block of Fig. 7 is the same as that shown in Fig. 6 except that instead of providing two tongues thereon, one tongue only, represented at 68, is provided. In the use of this particular form of block one notch only (not shown) to receive the tongue 68 would be provided in the lower cross rail portions of each of the compartments 38.

The pillow block of Fig. 8 provides a solid body portion 69 with an oblique face corresponding 20 with the web 58 and a face 70 at right angles to its end faces at which the block may seat against the lower cross rail of the compartment to which it is applied, the block having the tongue feature above referred to, exemplified in Fig. 8 by the 25 single tongue represented at 71 and corresponding with the tongue of Fig. 7.

In all of these constructions, the pillow blocks and cross walls of the compartments have co-operating parts, comprising the tongues of the 30 pillow blocks, which hold the blocks against displacement in a direction outwardly from the compartments, the blocks of Figs. 6 and 7 presenting the further feature of preventing displacement of these blocks lengthwise of the compartments.

In the particular construction shown, the compartments, the end walls of which are formed by the adjustable cross plates 37, are likewise adapted to receive pillow blocks for the purpose 40 stated. The pillow blocks for these compartments may be of any suitable construction, those shown being of the sheet metal type above described and extending at their edges 64 into grooves 71 in the upper surfaces of these cross plates. Where the pillow blocks used are provided with two tongues as in the case of the construction shown in Fig. 6, the cross plates would be provided with two registering notches in 45 their undersurfaces as shown at 72. Where the pillow blocks used are provided with a single tongue, as in the case of the construction shown in Fig. 7, the cross plates would be provided with one registering notch in their undersurfaces as shown at 73.

50 The compartment 29 is adapted to receive either the roman or italic type of matrices. For the roman type of matrices the block 30 would be used as the abutment for the composed line of matrices. For the italic type of matrices a pillow block 30^a would be used removably secured in place in any suitable way, as for example by a screw 30^b. The disposition of the parts referred to is such that the scale 32 accurately indicates the length of the composed 55 line of matrices whether of the roman or italic type. A recess 30^c in the bottom of the block 30 is provided to receive the pillow block 30^a when not in use. The arrangement just described is for a right-hand case.

70 Where this feature is to be incorporated in a left-hand case it may be provided as shown in Fig. 20, wherein the scale is represented at 100 and the block, corresponding to the block 30, at 101. The block 101 in this construction presents an oblique abutment face, as indicated at

102, for a column of matrices of the italic type, and to adapt it for the roman type of matrices a removable and replaceable pillow block 103 shown as held in place by a screw 104 is provided which when seated against the oblique face 102 presents a face 105 at right angles to the side walls of the compartment herein represented at 106 and corresponding to the compartment 29, and is in line with the zero marking of the scale 100. The block 101 also contains a recess 107 to receive the block 103 when not in use. The parts described are so disposed that the scale 100 is caused to accurately indicate a line of composed matrices in the compartment 106 when of either the roman or italic type. 15

While I have illustrated and described certain particular constructions embodying my invention, I do not wish to be understood as intending to limit it thereto as the same may be variously modified and altered and the invention embodied 20 in other forms of structure without departing from the spirit of my invention.

What I claim as new and desire to cover by Letters Patent is:

1. A matrix case having partitions forming compartments for matrices of different overall lengths and having body portions and ears extending in opposite directions therefrom, those of said partitions which form the side walls of said compartments being so spaced apart as to receive between them the body portions of the larger of said matrices and form supports for said ears and to receive between them the smaller of said matrices in their entirety. 30

2. A matrix case having partitions forming compartments for matrices of different overall lengths and having body portions and ears extending in opposite directions therefrom, those of said partitions which form the side walls of said compartments being of such width and so spaced apart as to receive between them the body portions of the larger of said matrices and form supports for said ears, with the ears of matrices in parallel adjacent compartments in non-overlapped relation to each other, and to receive between them the smaller of said matrices in their entirety. 40

3. A matrix case having a compartment for matrices either of rectangular or of non-rectangular parallelogram shape in plan, and a removable and replaceable pillow block in the lower end of said compartment and against which a column of matrices in said compartment rests, the surface of said block with which the column engages extending obliquely to the side walls of said compartment, and means comprising co-operating portions on said case and block restraining said block against displacement in a direction outwardly from said compartment. 50

4. A matrix case having a compartment for matrices either of rectangular or of non-rectangular parallelogram shape in plan and having cross walls, and a removable and replaceable pillow block in the lower end of said compartment and against which a column of matrices in said compartment rests, the surface of said block with which the column engages extending obliquely to the side walls of said compartment, the lower cross-wall of said compartment containing a recess and a projection on said block adapted to enter said recess and cooperate therewith to restrain said block against displacement in a direction outwardly from said compartment. 60

5. A matrix case having a compartment for matrices either of rectangular or of non-rec-

tangular parallelogram shape in plan and having cross walls, and a removable and replaceable pillow block in the lower end of said compartment and against which a column of matrices in said compartment rests, the surface of said block with which the column engages extending obliquely to the side walls of said compartment, and means comprising cooperating portions on said case and block restraining said block against displacement both in a direction outwardly from said compartment and in a direction lengthwise of said compartment away from the lower cross-wall of said compartment.

6. A matrix case having a compartment for matrices either of rectangular or of non-rectangular parallelogram shape in plan and having cross walls, and a removable and replaceable pillow block in the lower end of said compartment and against which a column of matrices in said compartment rests, the surface of said block with which the column engages extending obliquely to the side walls of said compartment, and a projection on said block lapping a portion of the lower cross-wall of said compartment in a position preventing displacement of said block lengthwise of said compartment in a direction away from the lower cross-wall of said compartment.

7. A matrix case having a compartment for matrices either of rectangular or of non-rectangular parallelogram shape in plan and having cross walls, and a removable and replaceable pillow block in the lower end of said compartment and against which a column of matrices in said compartment rests, the surface of said block with which the column engages extending obliquely to the side walls of said compartment, and a projection on said block engaging a portion of the lower cross-wall of said compartment in a position to prevent displacement of said block relative to the lower cross-wall of said compartment.

8. A matrix case having a compartment for matrices either of rectangular or of non-rectangular parallelogram shape in plan and having cross walls, and a removable and replaceable pillow block in the lower end of said compartment and against which a column of matrices in said compartment rests, the surface of said block with which the column engages extending obliquely to the side walls of said compartment, the lower cross-wall of said compartment containing a recess and a projection on said block adapted to enter said recess and cooperate therewith to restrain said block against displacement in a direction outwardly from said compartment, and means on said block engaging said lower cross-wall for preventing displacement of said block lengthwise of said compartment in a direction away from said cross-wall.

9. A matrix case having a compartment for matrices either of rectangular or of non-rectangular parallelogram shape in plan, and a removable and replaceable pillow block in the lower end of said compartment and against which a column of matrices in said compartment rests, the surface of said block with which the column engages extending obliquely to the side walls of said compartment, said block being formed of a web portion presenting said oblique surface and flanges extending therefrom, and means comprising cooperating portions on said case and block restraining said block against displacement in a direction outwardly from said compartment.

10. A matrix case having a compartment for matrices either of rectangular or of non-rectangular parallelogram shape in plan, and a

removable and replaceable pillow block in the lower end of said compartment and against which a column of matrices in said compartment rests, the surface of said block with which the column engages extending obliquely to the side walls of said compartment, said block being formed of a web portion presenting said oblique surface and flanges extending therefrom, and means comprising cooperating portions on said case and said flanges restraining said block against displacement in a direction outwardly from said compartment and in a direction lengthwise of said compartment.

11. A matrix case having a compartment for matrices either of rectangular or of non-rectangular parallelogram shape in plan, and a removable and replaceable pillow block in the lower end of said compartment and against which a column of matrices in said compartment rests, the surface of said block with which the column engages extending obliquely to the side walls of said compartment, said block having a face at the side thereof opposite said oblique surface at which it is adapted to bear against an end wall of the compartment, and means comprising cooperating portions on said case and block restraining said block against displacement in a direction outwardly from said compartment.

12. A matrix case having compartments for matrices, a compartment for receiving a composed line of matrices, and a scale extending along said last-referred-to compartment for measuring a composed line of matrices in said last-referred-to compartment.

13. A matrix case having compartments for matrices, a compartment for receiving a line of composed matrices, removable members in said last-referred-to compartment dividing the latter into several compartments, and a scale extending along said second-referred-to compartment for measuring a composed line of matrices charged into the latter.

14. A matrix case having a compartment for matrices either of rectangular or non-rectangular parallelogram shape in plan and having cross walls, and a removable and replaceable pillow block in the lower end of said compartment and against which a column of matrices in said compartment rests, the surface of said block with which the column engages extending obliquely to the side walls of said compartment, and means comprising cooperating portions on said case and block restraining said block against displacement in a direction away from the lower one of said cross walls and outwardly from said compartment.

15. A matrix case having a compartment for matrices either of rectangular or of non-rectangular parallelogram shape in plan, and a removable and replaceable pillow block in the lower end of said compartment and against which a column of matrices in said compartment rests, the surface of said block with which the column engages extending obliquely to the side walls of said compartment, said block being formed of a web portion presenting said oblique surface and flanges extending therefrom at its upper and lower edges, and means comprising cooperating portions on said case and block restraining said block against displacement in a direction outwardly from said compartment.

16. A matrix case having a compartment for matrices either of rectangular or of non-rectangular parallelogram shape in plan, and a removable and replaceable pillow block in the lower

end of said compartment and against which a column of matrices in said compartment rests, the surface of said block with which the column engages extending obliquely to the side walls of said compartment, a wall of said compartment containing a recess and a projection on said

block adapted to enter said recess and cooperate therewith to restrain said block against displacement in a direction outwardly from said compartment.

PHILIP P. MERRILL.

5
